UNITED STATES PATENT OFFICE.

WILLIAM KINGSLAND, OF GUNNERSBURY, COUNTY OF MIDDLESEX,
ENGLAND.

SECONDARY BATTERY.

SPECIFICATION forming part of Letters Patent No. 397,650, dated February 12, 1889.

Application filed June 4, 1888. Serial No. 275,944. (No model.) Patented in England April 22, 1887, No. 5,867.

To all whom it may concern:

Be it known that I, WILLIAM KINGSLAND, electrician, a subject of the Queen of Great Britain, residing at Gunnersbury, in the county of Middlesex, England, have invented certain new and useful Improvements in Secondary Batteries, (for which a patent has been granted to me in the following country: Great Britain, dated April 22, 1887, No. 5,867,) 5

10 of which the following is a specification.

My invention relates to that type of secondary battery which has for a negative element or anode a slab or plate consisting wholly or mainly of active material—such, 15 for example, as an agglomerate of peroxide of lead—electrical contact with which is effected by means of some inoxidizable metal, preferably platinum-foil, and my object is to minimize the amount of platinum required 20 and to use it to the best advantage.

The electrical contacts to which this invention relates are those joining the electrodes from cell to cell or with the main working-conductors of the apparatus; and in order 25 that my invention may be clearly understood and readily carried into effect I will describe the same with reference to the accompanying drawings.

Figure 1 represents in perspective a portion 30 of an anode composed of a slab or plate of active material, and showing the contact arrangement according to my invention. Fig. 2 is a partial vertical transverse section; and Fig. 3 is a side elevation of same with the plate D removed, and showing the bolt C in cross-section. Fig. 4 shows a similar form of connection in longitudinal and vertical cross-section arranged according to my invention and as applied to two plates. Fig. 5 is a plan, 40 and Fig. 6 is a vertical section on the line X Y, Fig. 5, showing a different arrangement of contacts. Fig. 7 is a plan of another somewhat similar arrangement, and Fig. 8 is a sectional view showing another arrangement for 45 connecting two plates.

According to my invention I employ contact pieces or strips of platinum-foil, A, which are clamped onto the anode B by means of nuts or bolts C, made of ebonite or other 50 suitable material, and I use in conjunction

with these a washer or cover or backing, D, for the platinum on that side which is not in contact with the anode, and this washer, cover, or backing is composed of one or more small pieces or strips of the same material as the 55 anode, cut to the required shape and size, so as to cover the platinum or contact-piece A, which is thus inclosed on each side with active material.

In constructing a cell containing two or 60 more anodes, B, I sometimes, as shown at Fig. 8, clamp the anodes together in pairs, with the platinum between, so that one piece of platinum may serve as a contact for two plates; or, when it is desirable to have a cathode, B', on each side of every anode B, I employ the aforesaid strip or washer of active material, D, as is shown at Figs. 4, 5, and 6, for a backing for the platinum, and I place the two anodes B B so that one strip of active 65 material, D, may serve as a backing for the platinum contacts A on each anode B; or I may employ two or more strips or washers of active material to form a backing for the platinum contacts, and also to separate the 70 anodes, so as to permit of a cathode being placed between them. I may also include the cathode B' in the above arrangement, and, as is shown at Fig. 7, clamp it between 75 the two anodes B B, making use for this purpose of the same nuts or bolts, C, which hold the anodes B B and their contacts A A together, suitable holes being made in the cathode B' for this purpose. In this case it will be necessary to employ a strip of some suitable 80 insulating material, as at D' D'—such as ebonite, or, preferably, india-rubber or asbestos—at those points where the cathode would otherwise be in contact with the active material of the backings. In clamping the 85 plates together I may also employ india-rubber or asbestos in the form of a washer, as shown at C', Figs. 5 and 7, underneath the heads of the nuts or bolts; or they may be applied in place of the insulating-strip D', in 90 order to give a certain amount of elasticity to the combination and to allow for expansion and contraction of the plates.

I am aware that it has been proposed to employ platinum in the construction of sec- 95 100

ondary batteries. I lay no claim to the use of platinum *per se*; but by my invention I am able to utilize its valuable qualities in a special and economical manner, and it is the 5 means which I employ for such purpose which forms the essential feature of my invention.

I claim—

1. In secondary batteries, the anodes B and platinum-foil contact-pieces A, in combination with the clamping washers or strips D, of similar material to the anode, and bolts and nuts C, as set forth.

2. The combination, with two or more anodes, B, and platinum-foil contact-pieces A, of 10 the distancing washers or strips D, of similar

material to the said anodes, and bolts and nuts C, as set forth.

3. The combination, with two or more anodes, B, cathode or cathodes B', and platinum-foil contact-pieces A, of the distancing strips 20 or pieces D, of the same material as the anodes B, insulating-washers D', and nuts and bolts C, as set forth.

WILLIAM KINGSLAND.
